O. PULLEN

THIMBLE

Filed April 2, 1926

Ovid Putton

Inventor

By *Cadmore & Co.*
Attorneys.

UNITED STATES PATENT OFFICE.

OVID PULLEN, OF HARMONY, NORTH CAROLINA.

THIMBLE.

Application filed April 2, 1926. Serial No. 99,304.

This invention aims to provide a novel means for mounting a cutting blade on a thimble, and to provide novel means for advancing and retracting the blade.

5 It is within the province of the disclosure to improve generally and to enhance the utility of devices of that type to which the invention appertains.

With the above and other objects in view 10 which will appear as the description proceeds, the invention resides in the combination and arrangement of parts and in the details of construction hereinafter described and claimed, it being understood that 15 changes in the precise embodiment of the invention herein disclosed, may be made within the scope of what is claimed, without departing from the spirit of the invention.

20 In the accompanying drawings:—

Figure 1 shows in plan, a device constructed in accordance with the invention; 25 Figure 2 is a longitudinal section; Figure 3 is a cross section.

25 The device forming the subject matter of this application is a thimble including an annular support or tubular body 1. The body 1 is shown as closed at its outer end 2, although this detail is not insisted upon.

30 At its rear end, the body 1 of the thimble has a bead 3. A notch 4 is formed in the bead 3. A tongue 5 outstands from the body 1 within the notch 4. A casing 6 of inverted trough-shape, is secured to the body 35 1 longitudinally thereof. At its rear end, the casing 6 is mounted in the notch 4. The tongue 5 extends into the rear end of the casing 6 and constitutes a closure therefor.

The forward end wall of the casing 6 is 40 marked by the numeral 7. There is an opening 8 in the end wall 7, the opening 8 being located close to the body 1 of the thimble. Near to its inner end and in its sides, the casing 6 has oppositely disposed

45 openings 9. In these openings 9, a ring 10 is held on the body 1 for rotation, the ring 10 turning in abutment with the bead 3, as Figures 1 and 3 will indicate clearly. Intermediate its edges, the ring 10 is supplied

with a raised rib 11. There are openings 12 50 in the rib 11. The openings have two purposes: first, they roughen the ring 10 sufficiently so that when the finger or thumb of an operator is placed on the ring, the ring can be rotated readily, and secondly, the 55 openings 12 form seats for the reception of the teeth of a gear wheel 14 secured to a shaft 15 that is mounted at one end to turn in the end wall 7 of the casing 6. The shaft 15 is threaded at 16 into a projecting finger 60 17 on the inner end of a cutting blade 18 mounted to slide on the body 1 of the thimble and guided in the opening 8 which exists in the end wall 7 of the casing 6.

In practical operation, when the ring 10 65 is rotated, the rotation will be imparted to the shaft 15, by way of the gear wheel 14, and the shaft, when rotated, will advance and retract the cutting blade 18, because the shaft is threaded at 16 into the finger 17 70 of the blade 18. The operator, thus, by a simple movement of the ring 10 circumferentially of the body 1, can advance the cutting blade 18 into the position shown in Figure 1, or retract it within the casing 6, 75 as delineated in Figure 2.

The utility of a blade on a thimble, and means for mounting the blade so that it can be advanced or retracted, will be obvious to those skilled in the art, but it may be stated, 80 briefly, that the blade when advanced into the position of Figure 2 may be used for ripping and for many other purposes. When the occasion for the use of the blade has passed, it may be retracted in the casing 85 6, as shown in Figure 2 of the drawings.

I claim:—

1. In a device of the class described, an annular support, a blade mounted for right-line reciprocation on the support, a member 90 mounted on the support for axial rotation with respect thereto, and means connecting the blade with said member to impart right-line reciprocation to the blade when said member is rotated.

2. In a device of the class described, an annular support, a blade mounted for right-line reciprocation on the support, a member

mounted to rotate on the support, and mechanism for transmitting motion from said member to the blade thereby to advance and retract the blade.

5 3. In a device of the class described, an annular support, a blade mounted for reciprocation on the support, a shaft supported for rotation on the support and threaded

into the blade, a pinion on the shaft, and a ring journaled on the support, the pinion 10 meshing into the ring.

In testimony that I claim the foregoing as my own, I have hereto affixed my signature.

OVID PULLEN.
